UNITED STATES PATENT OFFICE.

CARL H. FLODINE, OF CHICAGO, ILLINOIS.

WINDOW-CLEANING AND SPRINKLING DEVICE.

1,190,747.

Specification of Letters Patent. Patented July 11, 1916.

Application filed January 8, 1912. Serial No. 670,120.

To all whom it may concern:

Be it known that I, CARL H. FLODINE, a citizen of the United States, residing at Chicago, in the county of Cook and State of Illinois, have invented certain new and useful Improvements in Window-Cleaning and Sprinkling Devices, of which the following is a specification.

This invention relates to a household implement that can be used either as a window washer or, with slight adaptation, as a clothes or floor sprinkler, and it consists in an elongated, preferably cuneiform, receptacle of metal or suitable springy material, having minute perforations along the acute edge, which perforations are preferably covered with a strip of cloth when the device is used as a washer or cleaner, but are left free when it is employed as a sprinkler, suitable provision being made for filling it with an appropriate cleansing or dampening fluid, as soap-suds or pure water, or even disinfectant.

To enable this device to perform all the essential operations of window-cleaning, a drying member or squeegee preferably made of a fairly thick sheet of rubber, somewhat resilient and pliable, yet sufficiently stiff to remove liquid from a surface that has just been cleaned, is hingingly mounted on the ends of the receptacle near its operative edge, so that it is normally folded up against the side of the reservoir or vessel, but can readily be turned into its operative position by being projected forward to overlap the liquid-emitting edge.

In the drawings: Figure 1 is a perspective view, partly broken away, of a device embodying my invention, prepared for use as a sprinkler. Fig. 2 is a side elevation, partly in section, showing the device covered with a cloth or fabric, for use as a window washer. Fig. 3 is a cross-section therethrough on the correspondingly numbered line in the preceding figure, and Fig. 4 is a fragmental sectional view of a portion of the device showing the different layers of fabric or sponge or absorbent.

Referring now to said drawings: 4 is a receptacle of any suitable form, herein represented as cuneatic and elongated, having its long, acute edge 5 rounded and provided with minute perforations 6. The receptacle may be made of sheet metal or other equivalent material, advisably of a springy nature. Suitably located near the acute edge and

at one end of the device is a mouth 7 whereby it may be filled. A plug 8 which may be of cork, forms a stopper for this mouth.

As thus far described, the device may be filled with water and be used as a clothes sprinkler in laundry work, or for sprinkling floors preparatory to sweeping, or it may be charged with disinfecting or other fluid and employed to fumigate rooms or to give an agreeable odor to their atmosphere, a pressure on its walls facilitating the discharge of its contents, as in pocket oil-cans. When intended for use as a window cleaner, it will be filled with soap-suds or other cleansing fluid and the perforations in the acute edge will be covered with a strip of cloth or fabric 9, a layer of sponge or absorbent material 10, is then placed over the said cloth or fabric; and is in turn enveloped with another layer of cloth or fabric 11, which incases the entire device, except the end walls 12 and 13, but this is merely a matter of convenience, the effect being local to the immediate neighborhood of the perforations.

The inner strip of fabric 9 serves to distribute uniformly along the absorbent layer 10 the liquid projected through the minute perforations 6. Absorbent layer 10 serves primarily to retain the liquid thus made immediately available, storing it in quantities sufficient to be supplied and applied efficiently according to the needs varying with the amount of dirt to be removed from different parts of the surfaces to be cleaned, more or less liquid being squeezed from the absorbent reservoir to the cleansing layer proper 11, according to the greater or less force with which the receptacle is pressed against such surface, and to the rate of supply to the distributing layer 9, said rate depending on the pressure brought to bear on the springy sides of receptacle 4.

Removably pivoted, adjacent to the acute edges of the end walls 12, and 13, of the receptacle is a drying member or squeegee 14, so arranged that the same may be folded back and not interfere with the washing or cleansing process as in Figs. 2 and 3, of the drawings, but may be swung into the drying position as indicated in Fig. 1 of the drawing, after the cleansing process has taken place and the cleaned surface made ready for drying.

When it is desired to omit the absorbent, 10, the device may be used, in a measure, as

a sponge by alternately squeezing and releasing its walls, the effect being to first supply the cloth or cleansing surface with a surplus of fluid, and then to suck it back.

5 Primarily the device is intended to be used as a window-cleaning utensil, for which purpose it is normally equipped with the distributing, absorbing and applying or cleansing layers, and with the drying member. Removing one, or another, or all of 10 the layers, and swinging the squeegee up against the side of the receptacle, leaves the device available as a sprinkler, etc.

Having thus described my invention and 15 the best manner now known to me in which it may be applied, what I claim and desire to secure by Letters Patent of the United States is:

1. A squeegee consisting of a triangular 20 shaped prism having thin, flexible, converging side walls adapted to be compressed by the hand, a series of openings in the meeting edge of said walls, of such small size as normally to prevent water leaking 25 through, but adapted to direct water in a series of fine streams, when said sides are compressed.

2. A device of the character described comprising a triangular shaped prism hav-

ing a covered opening through which fluid 30 may be introduced, and having a rounded edge provided with minute perforations, the converging side walls which meet at said rounded edge, being made of thin flexible 35 metal adapted to be squeezed inwardly by hand to expel said fluid through said perforations, and a layer of fabric and absorbent material covering said perforations.

3. A device of the character described comprising a triangular shaped prism having a covered opening through which fluid may be introduced, and having a rounded edge provided with minute perforations, the converging side walls which meet at said rounded edge, being made of thin flexible 40 metal adapted to be squeezed inwardly by hand to expel said fluid through said perforations, a layer of absorbent material covering said perforations, and a squeegee pivoted to the end walls of the device and normally lying flat against one of said side walls out of the way of said rounded end, but adapted to swing outwardly and project beyond said end.

CARL H. FLODINE.
